(57) **CLAIM**

The ornamental design for a center base for battery carrying tray, as shown and described.

DESCRIPTION

FIG. 1 is a front, top, and left side perspective view of a center base for battery carrying tray, showing the claimed design;

FIG. 2 is a front view thereof and a back view thereof is identical;

FIG. 3 is a left side view thereof and a right side view thereof is identical;

FIG. 4 is a top view thereof;

FIG. 5 is a bottom view thereof; and,

FIG. 6 is a perspective view showing the center base for battery carrying tray in a state of use.

The broken lines shown in FIGS. 1-3 and 5 depict portions of the center base for battery carrying tray that form no part of the claimed design. The broken lines shown in FIG. 6 depict environment and form no part of the claimed design.
